ELECTRONIC AMPLIFIER ENCLOSURE HAVING AN END SEAL AND CURRENT FLOW BARRIER

Lyman L. Blackwell, 1515 Jasmine St.,
Denver, Colo. 80220

Filed Mar. 28, 1968, Ser. No. 11,162

Term of patent 14 years

Int. Cl. D14—04; D13—02
U.S. Cl. D26—14

FIG. 1.

FIG. 2.

FIG. 3.

FIGURE 1 is a frontal isometric view of an electronic amplifier enclosure having an end seal and current flow barrier showing my new design;

FIGURE 2 is a top view; and,

FIGURE 3 is a bottom view.

The rear view is a mere image of that of FIGURE 1.

I claim:

The ornamental design for an electronic amplifier enclosure having an end seal and current flow barrier, as shown and described.
